Primary Examiner — Cathron C Brooks(74) Attorney, Agent, or Firm — Tucker Ellis LLP(57) CLAIM

The ornamental design for a crib, as shown and described.

DESCRIPTION

FIG. 1 is a perspective view of a crib showing my new design;
 FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the crib that form no part of the claimed design.
